UNITED STATES PATENT OFFICE

WILLIAM L. WALKER, OF NEW YORK, N. Y., ASSIGNOR TO WALKER SIGNAL & EQUIPMENT CORPORATION, A CORPORATION OF DELAWARE

SUBMARINE SIGNALING APPARATUS

Application filed September 5, 1925, Serial No. 54,699. Renewed October 19, 1929.

My invention relates particularly to apparatus used in submarine signaling systems in which a plurality of microphones or other sound receiving apparatus are alternately placed in circuit with telephones or other indicating devices at the receiving station.

This invention also relates to switches that are designed to control a plurality of such electric circuits by the movement of a single switch handle into various positions depending upon the apparatus or devices designed to be placed in operation, but is applicable to other uses.

Unusual conditions must be met in the design and installation of switches such as are comprised in this invention owing to their use on shipboard where they are often surrounded by moist and salty air, in spite of which and other conditions the apparatus must be absolutely depended upon to function at the proper time with a minimum of attention and effort on the part of the operator.

In the present application I have described the details of a preferred form of switch which I have found to be very efficient and reliable in actual use and which may be installed within a small cabinet or box, together with other apparatus constituting the instruments employed in receiving submarine signals. The arrangement of the switches in relation to the other apparatus and instruments mentioned are described and claimed in my co-pending application, Serial No. 54,700 filed September 5, 1925.

In my present application I have described one arrangement of receiving circuits employed in receiving submarine signals and to which the switches of the present invention are particularly adapted.

For a detail description of the preferred form of my invention reference may be had to the following specification and to the accompanying drawings forming a part thereof, in which

Fig. 1 is a side elevation of my improved switch showing the panel on which it is mounted in section;

Fig. 2 is a transverse sectional view taken substantially on the line 2--2 of Fig. 1, and

Fig. 3 is a similar transverse sectional view

taken substantially on the line 3--3 of Fig. 1.

Fig. 4 is a horizontal or axial transverse sectional view taken substantially on the line 4--4 of Fig. 1.

Fig. 5 is a side elevation of one of the switch contact discs.

Fig. 6 is a side elevation of one of the short-circuiting discs.

Fig. 7 is a side elevation of one of the insulating washers which separate the contact discs, and

Fig. 8 is a schematic diagram of the connections constituting the circuits in which the switches may be employed.

Referring to Fig. 8 of the drawings, the circuit diagram will first be described. The letters P B indicate the port bow microphone, S B the starboard bow microphone, P A the port aft microphone and S A the starboard aft microphone. Obviously instead of having both bow and aft microphones, all of the microphones may be located at any other position in the length of the ship either midships or forward or aft in which case the letters A B indicate duplicate sets of microphones at the respective receiving points or ears of the receiving apparatus.

Referring further to Fig. 8, the numerals 1, 2, 3, 4 and 5 indicate respective contact discs which are rigidly mounted on a central shaft hereinafter to be more fully described so that they all turn simultaneously on said shaft, said discs being insulated from each other and from the shaft. Associated with each of the contact discs just referred to are a series of spring contact brushes or fingers indicated in the various positions by the numerals 27 to 40 inclusive, and 44 and 45 which will be referred to hereinafter. It will be noted that the brush 27 is adapted to bear upon the margin of the disc 5 at all times through an arc of slightly more than 90°, while the brushes 31 and 35 are adapted to bear upon the disc 5 only when the latter is turned 45° toward the respective positions in which they are located. In this way when the lower portion of the disc 5 is moved toward the right, the brushes 27 and 35 will be electrically connected together and if the lower portion of the disc 5 be moved toward the left, the brushes 31 and 45 will be connected together.

left, the brushes 27 and 31 will be connected together. This method of operation applies also to the discs 2, 3 and 4. As regards the short circuiting disc 1, the brushes 44 and 45 are connected together when the disc is in position as indicated in Fig. 8, but when turned 45° neither brush will contact with said disc. The switch in the upper portion of Fig. 8 constituting the contact discs 6, 7 and 8, operates in a similar manner to the switch previously referred to. Contacts 21 and 26 are always in contact with the discs 7 and 8 respectively, while the contacts 22, 23, 24 and 25 are adapted to contact when the discs are rotated 45° either clockwise or counter-clockwise. The short circuiting disc 6 also connects the brushes 39, 40 in the position shown in Fig. 8 but when turned 45° neither of said brushes contact with said disc.

Referring to the right hand of Fig. 8, the numeral 9 indicates a coil forming the winding of an audio frequency auto transformer. The numeral 10 indicates a condenser preferably of about 1 microfarad capacitance. The numerals 11, 12, 13 and 14 indicate the points to which connections are made with the auto transformer, and the numeral 15 indicates a switch for throwing the condenser 10 in shunt with the portion of coil 9. The numeral 16 indicates a condenser of about 2 microfarads capacitance. The numeral 17 indicates an impedance or choke coil, the purpose of which will be hereinafter described. The numeral 18 indicates a switch. The numeral 19 indicates a condenser of about $\frac{1}{10}$ of a microfarad capacitance for preventing sparking between the contacts of the switch 18, and 20 indicates a battery for energizing the microphones in the well-known manner. The numeral 50 indicates a rheostat having a series of contact points adapted to engage the movable arm 51 so that the auto transformer 9 may be shunted by more or less resistance depending upon the desired volume of the signals to be heard in the telephone.

Assuming now that it be desired to listen to the B microphone on the starboard side, the switch handles indicated on the extreme left of Fig. 8 are moved toward the left so that the pointer on the upper handle would indicate S and the pointer on the lower handle would indicate B. These movements will connect the brush 21 with the brush 22, the brush 26 with the brush 24, the brush 34 with the brush 30, the brush 33 with the brush 29, the brush 32 with the brush 28 and the brush 31 with the brush 27. It will thus be seen that the microphones P B and S B are so connected with the leads to the upper switch that either may be now thrown into circuit. The upper switch handle, however, having been turned toward S the contacts 22 and 24 are connected with the discs 7 and 8 respectively, and the microphone S B has been thrown into circuit by the movement

of the upper switch. The brushes 21 and 26 are connected respectively with the battery 20 and with the choke coil 17, from which the circuit passes through the lead 53 to the switch 18 and back to the battery 20. Thus the microphone is energized by constant direct current of the battery 20. When vibrations from the surrounding medium, such as sea water are impressed upon the microphones, the current therein will be varied and the variable component of the current will be conducted through the lead 52 running to the connecting point 12 of the auto transformer 9, emerging at the connecting point 11, passing through the condenser 16 and thence to the battery through the lead 53 and switch 18, thus the primary circuit of the transformer 9 is energized according to the received vibrations of the signal. The alternating field thus produced in the transformer 9, results in increasing the voltage of the alternating current which is conducted to the telephone 60, as follows:—

Through the connecting point 14, the current passes through the conductors 54, 55 and 56 to the telephone 60. The current then continues through the leads 57 and 59 to the contact point 11 thus completing the circuit through the secondary windings of the auto transformer 9. Since the discs 1 and 6 have been rotated as previously described the circuits between contacts 39 and 40 and between contacts 44 and 45 have been broken and hence the telephone 60 is not shunted. When the circuit has been established through the microphone S B as above described, the volume of the sounds produced in the telephones by microphonic action may be controlled in the following way:—

This control is of especial advantage where the received signals are accompanied by undesirable noises, such as water noises, propeller sounds and other noises which it is desired to distinguish from the musical note of a submarine signal. The reduction in the volume of sound will greatly reduce the undesirable noises without making the musical note of the signal inaudible. This reduction in the volume of the sound may be produced by moving the contact 51 over the variable resistance 50. It will be noted that the latter resistance forms a shunt between the extreme ends of the secondary coil of the auto transformer 9, thus the less resistance introduced the more of the signal current will be shunted away from the telephones and the volume of the signal correspondingly reduced.

On the other hand should it be desired to increase the volume of the signals, the switch 15 may be closed throwing the condenser 10 into shunt with a portion of the auto transformer coil 9. I have found that, owing to some reason which I cannot explain, the introduction of this condenser in this man-

5 ner greatly increases the volume of the received sounds, particularly the sounds from a submarine oscillator or bell as distinguished from water and other noises. As above stated, this condenser has a capacitance of about 1 microfarad. After having tried condensers of various capacitance in the same position, I find that this capacitance is particularly well adapted for purposes above described. The effect of the condenser is apparently not one of resonance because the electrical constants of the circuit are not such as to bring about that result. As above stated, I cannot explain the reason for the increase in the volume of signals, but I have discovered that a condenser located as described has this function to a remarkable extent.

It will be apparent from the above description that by turning the upper switch handle toward the right so that the pointer will indicate the letter P, the port microphones will be thrown into circuit; in this manner the port and starboard microphones may be compared as to their intensity and owing to the "shadow effect" of the hull of the vessel on the microphones the approximate direction of the source of sound may be determined in accordance with the volume of the sounds received in the respective microphones. When the vessel is pointed toward the source of sound, of course the volume of the sounds in the respective port and starboard microphones will be equal. Obviously, compensating devices may be connected with the microphone circuits so as to determine the direction of the sound, such as is described and claimed in my co-pending application Serial No. 25,011, filed April 22, 1925. However, I do not consider the latter necessary for the efficient operation of my improved signal receiving system herein described.

It will furthermore be understood that by turning the lower switch in Fig. 8 toward the left so that the pointer indicates the letter A, the contact brushes on the discs 2, 3, 4 and 5 will cause the microphones P A and S A to be connected with the upper switch, through which the respective starboard and port microphones of the A or aft group may be selected. It will be noted that when the discs 1 and 6 are turned 45° from the positions shown in Fig. 8, neither of the sets of contact brushes will engage said discs but when said discs are turned slightly in either direction from the position last noted, the contact brushes will immediately contact with the said discs, the contacts 44 and 45 being connected with the leads 55 and 57 of the telephone 60, movement of the disc 1 will short circuit the telephone. This prevents any click or sudden sounds being produced in the telephones when the contacts between the discs 2, 3, 4 and 5 are broken. In a similar manner the brushes 39 and 40 short

circuit the telephones when the disc 6 is turned simultaneously with the discs 7 and 8.

The details of the switch for producing the above mentioned connections will now be described.

Referring to Fig. 1, the numeral 61 indicates a supporting panel preferably made of insulating material to which is attached one of the end plates or frames 62 of the switch structure; this frame is connected with the opposite end frame 63 by means of longitudinal supporting pieces 64, 65, 66 and 67. Passing through the central points of the end frames 62 and 63 is the longitudinal shaft 68 (Fig. 4). This terminates in the right hand end in a reduced portion 69 on which is secured the operating handle 70. The hub of said handle is preferably provided with a pointer 71 to indicate the positions of the handle when the various microphones are in circuit, as indicated at the extreme left of Fig. 8. The shaft 68 is screw threaded on each end as indicated at 72 and 73, and is surrounded by insulating sleeve 74. On the screw threaded portion 73 is a disc 75 which is adapted to be retained rigidly in position by a set screw 76 or other suitable means. The screw threaded portion 72 of shaft 68 also carries a disc 77 against which bears a retaining nut 78. The right hand disc 75 is provided on its periphery with a series of transverse grooves 79, shown in dotted lines in Figs. 2 and 3, and in section in Fig. 4. These grooves are adapted to receive a small roller 80, indicated in Figs. 1 and 4, mounted on the end of a spring arm 81 which is attached to the longitudinal supporting plate 65. This serves to indicate to the operator when the switch has been turned accurately to any one of the three positions in which it is intended to be placed, because the roller entering the grooves retards the rotation of the switch at definite points. The end discs or plates 75 and 77 are connected by longitudinal rods 82, which, passing through corresponding holes in the various contact discs and washers, serve to hold them accurately in position on the shaft 68. The holes through the conducting discs 1 to 5 inclusive, as well as 6 to 8 inclusive, have insulating bushings as indicated at 83, Figs. 5 and 6. The end disc 75 is provided with a screw 84 forming a stop to limit the rotation of the switch when contacting with the screws 85 and 86 on the end plate 62. The contact discs of the switches having been assembled in the relative positions as indicated in Fig. 8, the same are thus mounted rigidly on the shaft 68 which is inserted between the end plates 62 and 63 so that the spring fingers 21 to 45 inclusive contact with the portions of said conducting discs which project above the insulating discs, as indicated in Figs. 1, 2 and 3. These spring fingers or brushes are mounted upon the longitudinal strips 64, 65

and 66 respectively, and are, of course, each insulated from said strips by suitable insulating sheets and bushings as indicated in Fig. 2. The machine screws which hold these brushes in position are provided with pairs of nuts which form the means for connecting the leads with the respective brushes as indicated at 87, in Figs. 2 and 3, the connections being made with said brushes as shown diagrammatically in Fig. 8.

From the above description it will be appreciated that I have produced a simple and efficient system for receiving sound signals and have included therein, switches of compact, efficient and durable design which may be installed in a comparatively small space, such as in a receiving cabinet of a type indicated in my co-pending application, Serial No. 54,700 above referred to.

Having thus described this form of my invention, I do not wish to be understood as being limited to the details of form and arrangements of parts and circuits indicated therein, for various changes may be made by those skilled in the art without departing from the spirit and scope of my invention as set forth in the accompanying claims.

What I claim and desire to protect by Letters Patent is:

1. Apparatus for receiving sound signals comprising, means for receiving sound waves and converting the same into correspondingly varying electric currents, a transformer, a switch for connecting said transformer in circuit with said receiving means, a condenser having greater capacity than that necessary for resonance at the frequencies to be received, being thereby adapted to eliminate extraneous noises, a switch for connecting said condenser with a portion of the secondary of said transformer and means in circuit with said transformer for detecting the variable currents produced by the vibrations of the received sounds.

2. Apparatus for receiving sound signals comprising, means for receiving sound waves and converting the same into correspondingly varying electric currents, an auto-transformer, a switch for connecting the primary winding of said transformer with said receiving means, means in circuit with the secondary winding of said transformer for detecting the variable currents produced by the vibrations of the received sounds, a condenser having greater capacity than that necessary for resonance at the frequencies to be received, being thereby adapted to eliminate extraneous noises, and a switch for connecting said condenser in shunt with a portion of the secondary of said transformer.

3. Apparatus for receiving sound signals comprising, a plurality of devices for receiving sound waves and converting the same into correspondingly varying electric currents, a transformer, a switch for selecting and con-

nnecting groups of said devices successively with said transformer, a condenser having greater capacity than that necessary for resonance at the frequencies to be received, being thereby adapted to eliminate extraneous noises, a switch for connecting said condenser with a portion of the secondary of said transformer and means in circuit with said transformer for detecting the variable currents produced by the vibrations of the received sounds.

4. Apparatus for receiving sound signals comprising, a plurality of devices for receiving sound waves and converting the same into correspondingly varying electric currents, a transformer, a switch for selecting and connecting groups of said devices successively with said transformer, a second switch for selecting and connecting the individual receiving devices of said groups with said transformer, a condenser having greater capacity than that necessary for resonance at the frequencies to be received, being thereby adapted to eliminate extraneous noises, a switch for connecting said condenser with a portion of the secondary of said transformer and means in circuit with said transformer for detecting the variable currents produced by the vibrations of the received sounds.

5. Apparatus for receiving sound signals comprising, a plurality of devices for receiving sound waves and converting the same into correspondingly varying electric currents, an auto-transformer, a switch for selecting and connecting groups of said devices successively with the primary winding of said transformer, means in circuit with the secondary winding of said transformer for detecting the variable currents produced by the vibrations of the received sounds, a condenser having greater capacity than that necessary for resonance at the frequencies to be received, being thereby adapted to eliminate extraneous noises, and a switch for connecting said condenser in shunt with a portion of the secondary of said transformer.

6. Apparatus for receiving sound signals comprising, a plurality of devices for receiving sound waves and converting the same into correspondingly varying electric currents, an auto-transformer, a switch for selecting and connecting groups of said devices successively with the primary winding of said transformer, a second switch for selecting and connecting the individual receiving devices of said groups with the primary winding of said transformer, means in circuit with the secondary winding of said transformer for detecting the variable currents produced by the vibrations of the received sounds, a condenser having greater capacity than that necessary for resonance at the frequencies to be received, being thereby adapted to eliminate extraneous noises, and a switch for con-

necting said condenser in shunt with a portion of the secondary of said transformer.

7. Apparatus for receiving sound signals comprising, means for receiving sound waves and converting the same into correspondingly varying electric currents, a transformer, a switch for connecting said transformer in circuit with said receiving means, means in circuit with said transformer for detecting the variable currents produced by the vibrations of the received sounds, a condenser having greater capacity than that necessary for resonance at the frequencies to be received, a switch for connecting said condenser in shunt with a portion of the secondary of said transformer to eliminate extraneous noises and a variable resistance in shunt with the secondary of said transformer to vary the volume of the received signals.

20 8. Apparatus for receiving sound signals comprising, a plurality of devices for receiving sound waves and converting the same into correspondingly varying electric currents, a transformer, a switch for selecting and connecting groups of said devices successively with said transformer, means in circuit with said transformer for detecting the variable currents produced by the vibrations of the received sounds, a condenser having greater capacity than that necessary for resonance at the frequencies to be received, a switch for connecting said condenser in shunt with a portion of the secondary of said transformer to eliminate extraneous noises and a variable resistance in shunt with the secondary of said transformer to vary the volume of the received signals.

9. Apparatus for receiving sound signals comprising, a plurality of devices for receiving sound waves and converting the same into correspondingly varying electric currents, a transformer, a switch for selecting and connecting groups of said devices successively with said transformer, a second switch for selecting and connecting the individual receiving devices of said groups with said transformer, means in circuit with said transformer for detecting the variable currents produced by the vibrations of the received sounds, a condenser having greater capacity than that necessary for resonance at the frequencies to be received, a switch for connecting said condenser in shunt with a portion of the secondary of said transformer to eliminate extraneous noises and a variable resistance in shunt with the secondary of said transformer to vary the volume of the received signals.

10. Apparatus for receiving sound signals comprising a plurality of devices for receiving sound waves and converting the same into correspondingly varying electric currents, an auto-transformer, a switch for selecting and connecting groups of said devices successively with the primary winding of said trans-

former, means in circuit with the secondary winding of said transformer for detecting the variable currents produced by the vibrations of the received sounds, a condenser having greater capacity than that necessary for resonance at the frequencies to be received, a switch for connecting said condenser in shunt with a portion of the secondary of said transformer to eliminate extraneous noises, and a variable resistance in shunt with the secondary of said transformer to vary the volume of the received signals.

70 11. Apparatus for receiving sound signals comprising a plurality of devices for receiving sound waves and converting the same into correspondingly varying electric currents, an auto-transformer, a switch for selecting and connecting groups of said devices successively with the primary winding of said transformer, a second switch for selecting and connecting the individual receiving devices of said groups with the primary winding of said transformer, means in circuit with the secondary winding of said transformer for detecting the variable currents produced by the vibrations of the received sounds, a condenser having greater capacity than that necessary for resonance at the frequencies to be received, a switch for connecting said condenser in shunt with a portion of the secondary of said transformer to eliminate extraneous noises, and a variable resistance in shunt with the secondary of said transformer to vary the volume of the received signals.

80 Signed at New York this 2nd day of September, 1925.
